UNITED STATES PATENT OFFICE.

CHARLES F. CHRISTMAN, OF WINSLOW, ARIZONA.

FIRE-ALARM SYSTEM.

1,143,809.

Specification of Letters Patent. Patented June 22, 1915.

Application filed May 19, 1914. Serial No. 839,610.

To all whom it may concern:

Be it known that I, CHARLES F. CHRISTMAN, a citizen of the United States, residing at Winslow, in the county of Navajo, State of Arizona, have invented certain new and useful Improvements in Fire-Alarm Systems; and I do hereby declare the following to be a full, clear, and exact description of the invention, such as will enable others skilled in the art to which it appertains to make and use the same.

This invention relates to fire alarms.

The principal object of the invention is to provide a fire alarm for towns wherein an audible signal is used to call volunteer firemen from their homes or places of business, the signal to be operated through the ordinary telephone call common in all small towns.

20 A second object of the invention is the provision, in an alarm of this character, of means to throw into operation a motor at the time that the signal is being given.

With the above and other objects in view 25 the invention consists in general of certain novel details of construction and combination of parts hereinafter fully described, illustrated in the accompanying drawings, and specifically claimed.

30 In the accompanying drawings, like characters of reference indicate like parts in the several views, and:—Figure 1 is an elevation of an apparatus showing this invention with the electric circuit connected there- 35 to shown in diagram. Fig. 2 is a vertical section of the circuit closer used herewith. Fig. 3 is a section on the line 3—3 of Fig. 2.

In carrying out the objects of the invention there is provided a suitable tank or 40 reservoir 10 and leading from this air tank or reservoir is a pipe 11 which carries on its upper end a whistle 12 of such size and type as to be readily heard throughout the district which is desired to be covered by 45 the alarm. In the pipe 11 is provided a valve 12' which is controlled by a magnet 13 so that when the magnet is energized the valve will open and when the magnet is de- 50 energized the valve will be closed by the action of a spring 14 connected to the valve lever 15 at one end and to the pipe 11 at the other. On this reservoir 10 is a pop valve 16 provided with an extended stem 17 carrying a contact bar 18 which engages the 55 fixed contact 19, this construction being of any preferred form. Connected to one of

these contacts 19 is a line wire 20 while to the other contact 19 is connected a wire 21 which extends to a motor 22. This motor 22 is connected through a train of gearing 23 with a crank disk 24 connected to the pit- 60 man 25 of an air pump 26 which is in turn connected to the reservoir 10 by means of a supply pipe 27.

At 28 is a magnetically controlled circuit closer the magnet of which is shown at 29 and leading from this circuit closer is a line wire 30 and a wire 31 which is connected to the motor 22. In order to energize the magnet 29 and 13 there is provided a battery 32 one pole of which is grounded as at 33. The other pole of this battery is connected by a wire 34 with the magnet 29 and from said magnet a wire 35 leads to the magnet 13. From the magnet 13 a wire 36 75 leads to an annunciator, the annunciator magnets being indicated at 37 and being connected in multiple to the wire 36. From each of these annunciator magnets leads a wire 38 which extends to the circuit closer 70 39 of a telephone. It is of course necessary to have separate circuit closers on the telephones but the telephone line wires are used for the purpose of transmission.

In the operation of the device if a fire 80 breaks out at any place the nearest telephonic circuit closer is closed whereupon a current will flow from the battery 32 through the magnet 29, magnet 13, and one of the magnets 37 corresponding to the circuit closer which is operated. This closes 85 a circuit through the motor and starts the motor to work. At the same time the valve 12' is opened and the whistle 12 blown. Also the annunciator drop governed by the 90 respective magnet 37 drops and discloses, in the central station, the exact location of the fire. The motor continues to operate and the whistle to blow as long as the circuit closer remains closed but this operation may be stopped by opening a switch 40' in the wire 33. If the air pressure becomes 95 too great the pop valve will open and thus break the circuit from the line wire 20 through the motor so that the motor will stop. This will not however stop the blowing of the whistle as the circuit through the magnets will still remain closed. If the air pressure drops the pop valve will of course close and the motor circuit will again 100 105 be established.

The preferred form of my pop valve is

shown in Fig. 2 in which 16' is a casing having exteriorly flanged and interiorly threaded top and bottom apertures 40 and 41 respectively. The bottom aperture being secured as above set forth to the air reservoir. Below the thread of the top aperture the casing 16' is cylindrical interiorly throughout most of its length and at the bottom of the cylindrical portion 42 is an annular shelf 43 constituting a valve seat adapted to engage the outer edge of the under side of the valve 44, said valve 44 has a peripheral packing ring 45 to enable it to snugly engage the interior wall of the casing when the valve is in motion. The valve stem 17 secured to the center of the valve 44 by means of a nut 46, said valve stem extending upwardly through and beyond the casing. A coil spring 47 surrounds the valve stem 17 and engages the upper surface of the shelf 43. The plug 48 is provided with a central aperture and having a peripheral thread on its lower portion engaging the threads of the aperture 41, this lower surface being forced down upon the spring 47 for producing on the spring 47 tension necessary to prevent the valve 44 from being raised before the air in the air reservoir has reached a predetermined pressure. Moreover the vertical aperture of the plug houses for slidable engagement a portion of the valve stem 17. A flange is formed in the upper portion of the plug 49 extends to the full width of the top of the casing in order that its under side may engage a washer rim 50 located between the top of the casing and the top of the plug. Secured by screws 51 to the upper surface of the plug is a plate of insulating material which carries binding posts 52 equidistant from the valve stem 17. Line wires 20 and 21 engage the binding posts and are secured thereto by the nuts 53. On the upper extremities of the binding posts are electric contacts 19. Secured to the upper extremities of the valve stem 17 is a yoke 54 which is made of conductive material and is provided with downwardly projecting arms 18. At the extremity of the arms being contact points 55 the length of the arms 18 being

such that when the valve 44 is in its seat 43 the contact points 55 will engage certain points 19 and close the current through the wires 20 and 21. When however, on account of excessive pressure the valve 44 is raised the contact points 55 will be displaced from contact points 19 and the circuit between the wires 20 and 21 be broken. To equalize the pressure between the interior of the casing and the outer air when the valve is operated a passage 56 is provided in the casing by means of which the air goes out when the valve 43 rises and enters the casing when the valve 43 falls.

There has thus been provided simple and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such as come properly within the scope claimed.

Having thus described the invention, what is claimed as new, is:—

In a device of the kind described, an electric motor, an air pump driven by said motor, an air reservoir connected to said pump, a pipe extending from said reservoir, an alarm whistle on said pipe, a valve in said pipe, a magnet for controlling the opening of said valve, a line wire connected to said motor, a circuit closer, a magnet connected in series to the first mentioned magnet and arranged to operate said circuit closer, a line wire connected to said circuit closer, a wire leading from the circuit closer to said motor, a battery connected in series to said magnets, and a series of circuit closers connected in multiple through said magnets.

In testimony whereof, I affix my signature, in the presence of two witnesses.

CHARLES F. CHRISTMAN.
